UNITED STATES PATENT OFFICE.

SAMUEL MURRAY, OF DUBLIN, ONTARIO, CANADA.

AUTOMATIC FIRE-ALARMS.

No. 876,384.

Specification of Letters Patent.

Patented Jan. 14, 1908.

Application filed April 20, 1907. Serial No. 369,332.

To all whom it may concern:

Be it known that I, SAMUEL MURRAY, of the village of Dublin, in the Province of Ontario, Canada, have invented certain new and useful Improvements in Automatic Fire-Alarms, of which the following is a specification.

My invention relates to fire alarms adapted to give a warning at a distance when a local rise of temperature occurs above a predetermined minimum, and my object is to devise an alarm of this type which will be simple, sensitive and reliable. I attain my object by the use of a bent compound metal band fixed at one end and connected at the other to a lever which on the bending of the band by heat is adapted to make contact with an adjustable contact piece whereby an electrical circuit is completed and an alarm given.

Figure 1 is a plan view showing my device in connection with a diagrammatically represented electrical alarm circuit. Fig. 2 is a side elevation, partly broken away, of the thermostat. Fig. 3 is a perspective view of a portion of the compound metal band of the thermostat.

In the drawings like letters of reference indicate corresponding parts in the different figures.

A is an electrical circuit in which B is a battery and C an electric bell.

The wires of the circuit are connected respectively to the binding posts D and E on the rosette F forming the base of the thermostat. The binding post E is in electrical contact with the bracket G, in which is fulcrumed a lever H. This lever is preferably formed as a cam lever, I being the cam.

J is a compound metal band fixed at one end to the stud K, suitably secured to the rosette F. This band is curved round, as shown, and its end has an opening therein through which the arm of the lever H passes so that a sliding connection is formed between the band and the lever. I consider this sliding connection preferable as no restraint is in any way placed upon the free bending of the metal band under the influence of heat.

On the binding post D is pivoted a contact arm L. A notched arc M is provided near the free end of the arm into any one of the notches of which the contact arm may

be sprung thus affording an adjustment of the contact arm to and from the cam lever.

The operation of the device is as follows:— Under the influence of an abnormal rise of temperature at the spot where the thermostat is located the compound band tends to straighten out, and this bending of the band rocks the cam lever and presses the cam against the contact arm L and thus completes the circuit, causing the bell to ring.

I find the cam lever preferable as it produces a rubbing contact with the contact arm, which rubbing action tends to produce a better electrical connection than a straight contact between two comparatively small surfaces, as the rubbing action tends to dislodge any small particles or inequalities which would operate to spoil the electrical connection. I do not, however, desire to limit myself to the use of this cam lever. It will be seen that by moving the contact arm the thermostat may be set to any desired temperature. As extreme cold has a tendency to cause the band to move the arm of the lever itself into contact with the contact arm I provide a stop N which limits the possible movement of the lever towards the contact arm and thus prevents such a contact occurring.

What I claim as my invention is:

1. The combination of a compound metal band fixed at one end; a cam suitably pivoted; a lever arm extending from the cam and to which the other end of the band is connected; and a contact piece with which the cam is adapted to contact when the latter is rocked by the movement of the lever arm by the bending of the compound metal band under the action of heat.

2. The combination of a compound metal band fixed at one end; a cam suitably pivoted; a lever arm extending from the cam and to which the other end of the band is connected; and a contact piece comprising a pivoted arm adjustable to and from the cam and with which the cam is adapted to contact when the latter is rocked by the movement of the lever arm by the bending of the compound metal band under the action of heat.

3. The combination of a metal band fixed at one end; a cam suitably pivoted; a lever arm extending from the cam and to which the other end of the band is connected; and

a pivoted adjusting contact piece with which the cam is adapted to contact at a point between its pivot and its end when the latter is moved by the bending of the metal band under the action of heat.

4. The combination of a metal band fixed at one end; a cam suitably pivoted; a lever arm extending from the cam and to which the other end of the band is connected; and 10 a pivoted adjusting contact piece with which the cam is adapted to contact when

the latter is moved by the bending of the metal band under the action of heat and a stop for preventing contact of the cam with the contact piece under the action of extreme cold. 15

Dublin, Ont., 12th April, 1907.

SAMUEL MURRAY.
